UNITED STATES PATENT OFFICE.

JOHN C. MCINTYRE, OF FARNHAM, NEW YORK.

BEATER FOR RUGS, ETC.

1,414,294.

Specification of Letters Patent. Patented Apr. 25, 1922.

Application filed June 21, 1920. Serial No. 390,631.

To all whom it may concern:

Be it known that I, JOHN C. MCINTYRE, a citizen of the United States, and resident of Farnham, in the county of Erie and 5 State of New York, have invented new and useful Improvements in Beaters for Rugs, Etc., of which the following is a specification.

This invention relates to a mechanical 10 rug, carpet, or fur beater for whipping or beating the dirt out of carpets, etc., in a manner somewhat similar to the ordinary manually operated carpet beaters.

One of the objects of the invention is to 15 provide a beater for rugs, etc., in which the operator is enabled to perform this rather messy carpet beating operation in a standing posture, so as to be considerably removed from the dust clouds which result from the 20 beating operation.

A further object of the invention is to 25 permit of a very strong beating or whipping action upon the carpet with a comparatively small but continuous force exerted by the operator, i. e. to beat the carpet with a pressure or force which is much heavier than the operator himself could exert directly with a hand rug or carpet beater.

A further object of the invention is to 30 provide an inexpensive and simple device of this character which may be very compactly folded up for storage or shipping purposes.

It is moreover the object of the invention 35 to provide a convenient and easily understood carpet beater in which the force of the blow delivered against the surface of the carpet may be suitably adjusted to suit the requirements of the carpet, rug or fur 40 which is being cleaned or renovated.

In the accompanying drawings:

Figure 1 is a side elevation of the complete improved beater with some of the beater blades removed. Figure 2 is a fragmentary, horizontal section through the crank case and associated parts and taken on line 2—2, Fig. 1. Figure 3 is a fragmentary vertical section through said crank case taken on line 3—3, Fig. 2. Figure 4 50 is a horizontal section through the complete beater taken on line 4—4, Fig. 1. Figure 5 is a side elevation of the beater in its compactly folded position. Figure 6 is a view 55 similar to Fig. 3, showing the parts associated with the crank case in a different po-

sition. Figures 7, 8, 9 and 10 are views of modified forms of the invention.

Similar characters of reference indicate corresponding parts throughout the several views.

This improved beater for carpets, rugs, furs, etc., may be modified considerably in mechanical structural details within the scope of this invention, but the particular embodiment thereof shown in the drawings 60 has proven very satisfactory and hence is preferred, and as there illustrated is constructed as follows:

The main frame of the beater comprises a base, pedestal or foot plate 10 and an 70 upright post or standard 11 which is preferably secured and braced to said base by means of suitable stiffening braces 12. 13 represents a plurality of elastic whips or beater blades which are preferably constructed of second growth hickory or similar springy, resilient material. These beater blades are suitably secured together by means of a pair of transverse tie bars 14 and 140, which are secured to said beater 80 blades by bolts 15 or otherwise. Riveted or otherwise secured to the companion upturned ends of the tie bars 14 and 140 are a pair of hinge plates 16 and 160 which 85 swing about the pivot studs or pintles 17 and 170 of the hinge blocks 18 and 180, said hinge blocks being screwed or otherwise secured to the base 10 of the beater. Thus all of the beater blades 13 are able to move 90 in unison up and down about the pintles 17 and 170 as an axis.

Secured centrally of the beater to the upper faces of the tie bars 14 and 140 is an L-shaped bracket arm 20 which extends considerably rearwardly and then upwardly 95 of said tie bars, the same being given a sharp bend or offset 21 so as to properly clear the adjacent corner of the beater base 10 when said bracket arm is in its lowermost position, i. e. when the beater blades 13 are 100 horizontal. Detachably secured by means of a hook 22 to the upper end of said bracket arm 20, is a helical tension spring 23. The forward end of this spring is permanently connected to the forward downturned end 105 of a spring adjusting rod 24 which is longitudinally-slidable in, and is adjustable relatively to, a spring block 25, the rod being retained in its properly adjusted position by means of a set screw or other adjusting screw 110

26. Thus by moving this rod either forwardly or backwardly, the desired tension of the spring 23 may be secured and the adjustable rod locked in place by means of 5 the said set screw 26.

This spring 23 tends to always depress the beater blades downwardly, so as to snap or whip the same downwardly against the upper horizontal surface of the carpet, rug 10 or fur which is being beaten. For this purpose of course a sufficient amount of potential energy must be stored in the spring. This is obtained by elevating or raising the beater blades in the following novel manner:

15 Pivots connected to the beater blades (for instance by a pivot plate 27 which is bolted to the upper forward part of the bracket arm 20) is an upright connecting rod 28 whose upper end is pivoted to the lower end of a vertical slip plate 30. This slip plate bears loosely and slidably against the front face of a cylindrical or cup-shaped crank case 31 upon whose opposite front edges are formed the outwardly, longitudinally extending projections or flat bosses 32, 25 Figs. 3 and 6. Against the front faces of said bosses 32 is secured (by the countersunk screws 33 or otherwise,) a retaining plate 34 which is disposed in spaced relationship 30 relatively to the outer edge of the crank case 31.

The intervening space between the front face of the crank case and the rear face of the said retaining plate 34 receives the said 35 vertical slip plate 30, which moves both vertically and transversely relatively to said crank case. Journaled concentrically in the rear vertical wall of the crank case, as shown in Fig. 2, is a crank shaft 35, the rear end of 40 the same being preferably journaled in a suitable journal 36 which is secured to the upright standard 11 of the main frame of the beater. The extreme rear end of said crank shaft 35 is provided with a laterally-extending arm 37 whose outer end carries a rotatable handle 38 which enables the operator to grasp the said handle and manually rotate the crank shaft in one direction continuously, i. e. in the direction indicated by 45 the arrows. The forward end of said crank shaft 35 is provided with a crank arm 40 whose outer end is pointed and curved or bent at 41 in a direction forwardly of the direction of rotation of the crank arm.

50 55 Formed integrally upon the rear face of the slip plate 30 is a rearwardly and inwardly or laterally-extending post, stud or lug 42. When the beater blades 13 are in their lowermost or depressed position, this 60 lug is positioned in the lower part of the crank case, as shown in Fig. 6. As the crank shaft is rotated, the pointed end 41 of the crank arm thereof picks up and moves upwardly the said lug 42, carrying with it the slip plate 30 and hence also the connecting

rod 28 and the beater blades 13 which are pivoted to the lower end of said connecting rod. It will be noted from Fig. 3, that there would be a tendency of the said lug 42 to slip inwardly off of the crank arm as the 70 latter moves up above its horizontal or half-stroke position. Such an action is frustrated by forming a forwardly-facing or inwardly projecting arcuate guide, bead or flange 44 on the inner face of the rear wall of the crank case. The upper end of this arcuate guide terminates abruptly at 440 so that when the lug 42 reaches the upper end of its stroke, it moves clear of said guide 44, whereupon said lug, together with the beater blades 13 and all 80 intermediate connecting parts, moves suddenly and powerfully downwardly under the influence of the tension spring 23 and until the beater blades come forcibly sharply in contact with the carpet, rug or fur which is 85 being beaten and cleaned. Then the crank shaft and the crank arm are further rotated until said crank arm and lug 42 again assume the positions of Fig. 6 and the cycle of operations then continued.

90 The folding feature of this improved rug or carpet beater makes for very great convenience in storing or shipping the same. To fold the beater, the hook 22 at the rear end of the tension spring 23 is first uncoupled from 95 the upper end of the bracket arm 20, this operation being preferably effected when the beater blades 13 are in their depressed or horizontal position. These beater blades are then elevated to the position shown in 100 Fig. 5, which causes the outer tip of the bracket arm 20 to assume such a position that when a turn button 46 is moved horizontally about its vertical pivot 47, the front end of the same is caused to swing over the upper 105 face of the outer end of said bracket arm 20, thereby securely holding said bracket arm in this position and hence the beater blades 13 in their elevated position.

110 The spring adjusting rod 24 is also folded up out of the way for purposes of compactness, this result being obtained by pivoting the spring block 25 (on which is mounted the said adjusting spring bar) at 48 to the upright post 11 of the beater frame. As shown 115 in Figs. 1 and 5, the downward movement of this spring block 25 is prevented, when the beater is being used, by means of a spring block stop 50, which is secured to the upright post 11 of the beater and is adapted to engage with the lower rear face of said spring block.

120 In the operation of the improved beater, the operator preferably places one of his feet upon the base or pedestal 10 of the stationary beater frame and manually and continuously turns the handle 38 of the crank shaft 35 until the carpet, rug or fur is beaten sufficiently. The force which causes 125 the beater blades 13 to be powerfully and 130

suddenly depressed against the upper surface of the carpet is derived from the tension spring 23 whose pressure may be regulated by adjustably moving the same forwardly or backwardly in the spring block 25 and locked in place by means of the set screw 26. The pressure of the said tension spring 23 is delivered suddenly and forcibly but the potential energy which is stored in the 10 spring is obtained during a relatively greater length of time, that is, while the crank shaft 35 and its crank arm 40 are making an upwardly moving half revolution. Thus, a weak person can, with this improved carpet beater, deliver a forcible blow which is much more powerful than he could obtain with an ordinary hand carpet beater. The folding up of the beater is accomplished by unhooking the hook 22 of the tension spring 20 23 and then raising the beater blades to the position of Fig. 5 and securing it in position by means of a turn button 46. The spring adjusting rod 24 is also folded up, the spring block being pivoted at 48 and limited 25 in its downward movement by reason of a stop 50.

In the modification of the invention shown in Fig. 7 is shown a construction in which the connecting rod 280 (and hence also the beater blades) is reciprocated twice for every one revolution of the manual operating arm 370. The latter is connected to a crank shaft 350 similarly to the previously described constructions, said crank shaft 35 being adapted to be manually rotated continuously in the one direction by means of said arm 370. Keyed or otherwise secured at its central part to said crank shaft is a slotted yoke arm 55, which is arranged to 40 rotate within the crank case 310, and extends laterally outwardly an equal distance on each side of the axis of said crank shaft. The diametrically and laterally disposed slot in said slotted yoke arm 55 is adapted to receive the stud 420 of the slip plate 300, said stud being at all times confined within said slot. When this said stud 420 has been lifted up above the position shown in Fig. 7 (by reason of the continued rotation of the manual operating arm 370), then said stud moves inwardly and downwardly within said slot similarly to the movement of the analogous stud 42 of Figs. 1-6. The falling of said stud permits the slip plate 300 and hence 45 also the connecting rod 280 to move forcibly downwardly, thereby allowing the beater blades (not shown) to beat or pound the dirt and dust, out of the carpet, rug or fur which is being renovated. When the slot of said 50 slotted yoke arm 55 arrives at a vertical position, the aforesaid stud 420, which is then lying in the lower end thereof, is again picked up and the whole cycle is repeated as often as desired.

65 In Figs. 8 and 9 is shown a very simple

and commercially valuable embodiment of the invention in which the beater blades 113 are reciprocated twice for every one revolution of its manual operating arm 137. The latter is secured to a crank shaft 135, which, in turn, is secured to a crank arm 140. The latter is straddled by a U-shaped lifting yoke 56 shown in perspective in Fig. 9, whose arms are arranged longitudinally on either side of the hub of the crank arm 140 and are loosely journaled on the crank shaft 135. A modified connecting rod 128 is pivoted to the outer end of said U-shaped lifting yoke, the upper end of said connecting rod being provided with a transverse arm 57 which extends through and is journaled in holes 58 which are formed in the legs of said lifting yoke. A further rotation in the direction of the arrow of the manual operating arm 137 and of the crank arm 140 from the position of the same shown in Fig. 8, causes said crank arm 140 to bear against the transverse arm 57 of the said connecting rod, thereby carrying with it the yoke 56 and continuing to do so until the said crank arm 140 arrives at a substantially vertical upward position. Thereupon, the tension spring 123 causes the said connecting rod and the lifting yoke to be violently pulled downwardly together with the beater blades 113. A still further rotation of the manual operating arm 137 brings the said crank arm to a substantially vertical downward position whereupon the same again contacts with the transverse arm 57 of the connecting rod. 90

The latter is then again lifted until it reaches the top of its stroke, whereupon it again is free to violently and quickly descend, allowing the beater blade to beat the carpet.

A still further very simple modification of the invention is shown in Fig. 10. Here the beater blades are mounted on a suitable frame which is pivoted at 60 and which is provided with a laterally extending finger 61. Pivoted at 62 to the base 100 of this modified beater is an operating lever 63, to which is pivoted a T-shaped trip dog 64. The lower or inner end or nose of said dog is arranged on one side of the operating lever while the upper end is offset and is adapted to bear against the front face of said lever, as shown in the full lines of Fig. 10. By reason of the difference in location or eccentricity of the pivots 60 and 62, the dog 64 clears the outer end of the finger 61 when the lever is moved a short distance rearwardly of the full line position of Fig. 10. When this occurs, the tension spring 66 causes the beater blades to be violently depressed similarly to the action thereof in the other embodiments of the invention. To complete the cycle of operations, the operating handle 63 is then moved forwardly, thereby causing the pivoted dog 64 to trip over the outer end of the finger 61 and en-

gage the front side thereof, whereupon the operating lever may again be pulled rearwardly and the cycle of operations continued as before. To resiliently hold the dog 64 5 with its upper end bearing rearwardly against the front face of the operating lever 63, a compression spring 67 is employed which is suitably arranged so as to ensure this resilient action.

10 It is obvious that in all forms of the invention the tension springs which cause the beater blades to be suddenly depressed may be replaced by suitable weights which cause a force tending constantly to depress said blades. Furthermore, it is obvious that, in 15 the modification shown in Fig. 10, a suitable irregular rotating cam may be used instead of the oscillating tripping arrangement illustrated.

20 I claim as my invention:

1. A beater for rugs, etc., comprising a frame, a beater blade pivoted to said frame, a spring operating to depress said beater blade, a connecting rod, a crank case, a 25 crank shaft having its crank arm arranged

within said crank case, a slip plate provided with a lug and slidably arranged within said crank case.

2. A beater for rugs, etc., comprising a frame, a beater blade, a spring operating to 30 depress said beater blade, a connecting rod, a crank case, a crank shaft having its crank arm arranged within said crank case, a slip plate having a lug, and an arcuate 35 guide arranged within said crank case and adapted to guide the lug of said slip plate and prevent the same from moving downwardly after the crank arm of said crank shaft has reached midstroke.

3. A beater for rugs, etc., comprising a frame, a beater blade, a spring block pivoted to said frame, a spring block stop arranged on said frame, a spring adjusting rod adjustably connected to said spring block, a 40 spring connected at opposite ends to said beater blade and to said spring adjusting rod, and means for intermittently elevating and releasing said beater blade. 45

JOHN C. McINTYRE.

Certificate of Correction.

It is hereby certified that in Letters Patent No. 1,414,294, granted April 25, 1922, upon the application of John C. McIntyre, of Farnham, New York, for an improvement in "Beaters for Rugs, Etc.," errors appear in the printed specification requiring correction as follows: Page 4, after line 39 insert the following as claim 3:

3. A beater for rugs, etc., comprising a frame, a beater blade, a spring operating to depress said beater blade, a connecting rod, a crank case, a crank, and a slip plate vertically and transversely slidable relatively to said crank case and provided with a lug which is adapted to intermittently engage with said crank.;

same page, line 40, for claim number "3" read 4; and that the said Letters Patent should be read with these corrections therein that the same may conform to the record of the case in the Patent Office.

Signed and sealed this 13th day of June, A. D., 1922.

[SEAL.]

KARL FENNING,
Acting Commissioner of Patents.
